Chicago, Ill.

Application November 21, 1936, Serial No. 112,108

13 Claims. (Cl. 200—98)

This invention relates to a selector usable in vending or amusement apparatus of various kinds for manually selecting one of a number of electric circuits including an open switch. Under any desired condition of use the switch may be closed to complete a circuit for a motor, relay or other motor device to accomplish some result, such as the vending of an article.

The invention relates specifically to the selector structure per se, the same preferably embodying a unit mountable in a cabinet for the apparatus with which the selector is to be used. The selector thus comprises broadly a support of some kind carrying a shifter bar movable manually by a control including visual means serving as an indicator to facilitate selection of any one of a plurality of circuits and the respective open switch therein. The bar carries an electromagnetic coil, which is normally deenergized and when a selection has been made, is located in line with the switch of the selected circuit. Thereafter, when the coil is energized, its armature moves to close the open switch and complete the selected circuit to accomplish the result which said completed circuit is intended to perform. Associated with each said switch is a lever operable by the coil armature and serving to open or close the switch, there being further provided for each lever a novel latch means releasably to hold the lever in either switch closing or switch opening position. After a lever has moved to switch closing position a reset mechanism may be operated to restore the lever to switch opening position.

The main object of the invention is to provide an improved selector mechanism for the purposes stated.

Another object is to provide an improved means for closing a selected switch.

Another object is to provide an improved resetting mechanism to restore a switch that has been closed, to open position.

Still another object of the invention is to provide a simple means for releasably holding the selector in any selected position.

Another object of the invention is to provide a selector of the kind stated, comprising a small compact unit, which will be foolproof in use and not be likely to get out of order.

Other important objects will become apparent to those versed in this art as the disclosure is more fully made.

In the accompanying sheets of drawings illustrating one form which the invention may assume in practice:

Figure 1 is a general, perspective, elevational view of a cabinet, the front wall of which carries the selector unit of this invention;

Figure 2 is a general, plan view of the selector mounted in the cabinet with the top of the latter removed to expose the selector structure;

Figure 3 is a vertical, longitudinal cross sectional view through the structure, taken along the line 3—3 of Figure 2, looking in the direction of the arrows;

Figure 4 is a rear view of the selector;

Figure 5 is an end elevational view with the near side of the cabinet removed for the sake of clearness;

Figure 6 is a cross sectional view taken through the structure along the line 6—6 of Figure 3, looking in the indicated direction;

Figure 7 is a detail, sectional view taken along the line 7—7 of Figure 5, looking in the direction of the arrows; and,

Figure 8 is a typical wiring diagram to show an organization in which the selector is useful.

A cabinet of any desirable kind housing an apparatus with which the present selector is usable is generally indicated at 10, said housing having a front wall 11 in which the selector may, for the sake of illustration be mounted, as will presently appear. As appears best in Figures 1 and 2, the front wall 11 on its exterior face carries a guide block 12, marked off with guide lines numbered for example from one to six and corresponding to a like number of open switches and respective electric circuits to be selected by the selector mechanism. This block 12 is formed with a transverse, elongated, guide slot 13 in which as shown in Figure 3 is slidably carried the stem 14 of a knob handle member 15. Said knob includes a depending finger portion 16 and an upstanding tell-tale pointer extension 17, which may be positioned relative to the numbered indicator lines on the guide block 12, in an obvious manner. The stem 14 passes longitudinally rearwardly as shown in Figure 3 and through a transverse, elongated slot 18 formed in the wall 11, said stem being surrounded by a collar 19, as shown.

The rear end of the stem 14 is thus located behind the wall 11 where it is rigidly secured, as by welding, to a transversely disposed plate or bar 20. Obviously, when the knob 15 is moved side-wise, the plate 20 must move bodily with it. The selector unit disposed behind the wall 11 comprises a suitable supporting frame attached to the wall 11, said frame embodying an upper and lower plate 21, spaced apart as shown in

Figure 3. Secured to the rear side of these plates as by welding is a U-shaped, or channel shaped bracket 22 the bight of which lies flatly against the plates 21. Said bracket provides two longitudinally extending and transversely spaced vertical walls 23, 24, the rear ends of which are cross braced by a transverse vertical plate 25. This frame unit may be secured to the rear face of the wall 11 by means of screws 26. The end walls 24, 25 are cut out as at 27 to allow the plate 20 in its lateral shifting movement to pass through said walls.

The lower edge of the plate 20, as shown in Figures 3 and 6, is formed with a corrugation, providing six notches 28. Below these notches the frame part 22 carries a longitudinal screw bolt 29 pivotally carrying one end of a pivotal lever 30 on the free end of which is a roller 31 to engage in said notches 28. Between the lever 30 and plate 22 the bolt 29 is surrounded by a spacer sleeve 32 around which is coiled a spring 33, opposite legs of which are connected between the plate 22 and lever 30 in such a manner that the latter is always yieldingly pressed upwardly to seat the roller 31 in a notch 28.

Substantially midway between its ends the shifter plate or bar 20 has rigidly secured to its back side a bracket 34 for carrying a solenoid 35 the armature 36 of which is horizontally and longitudinally disposed. This solenoid obviously shifts with the bar 20. The solenoid by means of wires 37 is placed in circuit with a source of energy, such for example, as a battery 38, said circuit normally being open by any suitable form 35 of switch, such for example as the push button switch 39 shown, which further by way of example may be mounted on the front wall 11.

As seen best in Figures 2, 3, and 4 the cross plate 25 carries six spaced insulator blocks 40, each carrying a pair of upstanding spring switch arms 41 the contacts at the upper ends of which are normally gapped apart because of the springiness in the arms 41. Incidentally, these switches 41 respectively line up longitudinally with the six notches 28 and the numbered marker lines on the block 12.

A shaft 42 is transversely carried in the end walls 23, 24 at a point forwardly of the switch carrying bar 25 as shown in Figure 3. This shaft carries a series of independently mounted spacer sleeves 43, of which there are six in the present disclosure respectively including an upstanding arm 44. These arms or levers 44 respectively line up with the switches 41. Each lever at its upper end facing the switches 41 carries an insulated roller 45, said rollers adapted, when the arms 44 are swung rearwardly to engage and hold closed the adjacent switch arms 41 in an obvious manner. The rearward movement of each lever arm 44 is limited by means of a transverse shaft 46. One side of each switch 41 is connected by a tap 47 to a main line wire 49 as shown in Figure 3 that goes to the source of energy 38. A main line wire 49 leads from the source of energy to one side respectively of a number of electromagnetic motor devices, such as the relay coils 50 shown, for illustrative purposes only. The other side of each relay 50 is connected by a respective tap 51 to the opposite side of the respective switches 41. It can now be appreciated that when any switch 41 is closed a corresponding circuit for a relay 50 is completed to energize the latter and cause its operation for any desired purpose.

A latch means individual to each lever 44 is provided whereby each said lever 44 is releasably

held latched or locked in either switch 41 opening position or switch closing position. This latching means will next be described. At a point above and in front of the top ends of the levers 44 the end walls 23, 24 carry a cross shaft 52. Said shaft carries six spacer sleeves 53 independently mounted for rocking movement on the shaft 52, and each sleeve being formed with a bell crank lever having a rearwardly extending arm 54 and a downwardly extending arm 55. The downwardly extending arm 55 of each said bell crank lever has hooked to it one end of a tension spring 56, the opposite ends of said springs being hooked over a transverse shaft 57 in the manner shown in Figures 2 and 3. 15

The leg or arm 54 of each bell crank lever has its under edge notched out to provide two steps 58 and 59. The springs 56, it will now be seen, serve to pull the extensions 54 downwardly so that when an associated lever 44 is in switch 41 closing position, as seen in dotted lines in Figure 3, the step 59 is effective to engage the top end of the lever 44 yieldably to latch it in such position; and, when the lever 44 is in the full line, switch opening position, then the step 58 is effective to engage the top end of the lever 44 and thus hold the lever latched in its other position. A reset means is also provided to enable restoration to normal position of any lever 44 that may have been moved to close a switch, and such 30 means will now be described.

The end walls 23, 24 carry in a position above and forwardly of the shaft 52, a transverse shaft 60. (See Figures 3, 5, and 7.) On this shaft 60 is pivotally hung a bail shaped lever 61, opposite legs of which may be pressed by a spring 62 mounted in any suitable manner to swing the lever 61 normally forwardly. Said lever bail 61 is so positioned that when it is swung rearwardly it will engage any bell crank 54 that may have been lowered to the dotted line position shown in Figure 3. The bail lever 61 is swung against the pressure of the spring means 62 by mechanism comprising a reset relay or solenoid 63 carried on the wall 23 on its outer side, by means of a suitable bracket 64. This solenoid has an armature, or movable core 65, which at its free end is notched, as at 66 for the reception of a transverse pin 67 carried at the lower end of a pendant lever 68 which at its upper end is fulcrumed on the extended end of the shaft 60 as best shown in Figure 7. An intermediate portion of the lever 68 carries rigidly a transverse pin 69 connected in any desired manner rigidly to the adjacent end of the bail lever 61 and passing through an arcuate slot 70 in the adjacent wall 23 to make such connection possible. 45

As seen best in Figures 2 and 8 this reset solenoid 63 is connected at one side by a wire 71 to the wire 48 and battery 38, while the other side 60 thereof is connected by a wire 72 with a push button switch 73 mounted in any convenient place as shown. A wire 74 may lead from said switch 73 to the source of energy to complete a circuit as will now be clear. This completes the detailed description of the parts of the improved selector. Its mode of operation and use will now be summarized.

Each of the six switches 41 is normally open and as a result the circuits which they respectively control to the motor devices 50 are also open with the devices 50 deenergized. The number of the switches 41 can be varied to suit requirements. Six have herein been shown merely for the sake of illustration. Further, the cir- 75

cuits controlled by the switches 41 can be so arranged by one skilled in the art as to control but a single motor device common to all circuits, if desired.

5 Continuing with the description, each lever arm 44 is in the full line position shown in Figure 3, the bell crank latches 54 and the reset bail 61 also being shown in full lines in said figure in their normal starting positions. We will assume 10 that it is desired to select and operate any one of the six circuits for a device 50 and to close the switch 41 therefor to cause energization of the selected device. Accordingly, the operator grasps the knob 15, 16 and shifts the same to the 15 selected numbered line position appearing on the block 12. This, of course, moves the stem 14 and bar 20, and with it the solenoid 35. The roller 31 of the spring pressed lever 30 yieldably rides in and out of the notches 28 in the bar or plate 20 20 until the latter has been brought to rest in its selected position of adjustment. When the bar 20 is brought to rest in the selected position the roller 31 releasably and yieldably locks the plate 20 in such position. The solenoid 35 is now longitudinally alined with a lever 44 and associated switch 41 in a manner that will be readily understood.

The operator next closes the button switch 39 to complete a circuit to cause energization of the 30 solenoid 35 whereupon its core 36 is projected rearwardly to engage and push the lever 44 rearwardly, causing its roller 45 to engage and press the alined spring switch 41 rearwardly to close its contacts in the manner shown in the dotted 35 lines in Figure 3. With the switch 41 closed a circuit is completed to energize the device 50 therein for any purpose desired, such for example, as to operate a vender to dispense an article. The switch 41 thus selected is positively 40 held closed by the notch 59 of the associated bell crank lever 54 in the manner heretofore described. See the dotted line position of a lever 54 in Figure 3.

In resetting the lever 44 to reopen the closed switch 41, the operator pushes the button 73 to complete a circuit for energization of the reset solenoid 63, thus through the connections described, to swing the bail lever 61 rearwardly to engage the cocked bell crank lever 54 and push it to its raised position, thus freeing the rearwardly swung lever 44. As the spring switch arms 41 snap back to their true upright position to open the switch contacts, the lever 44 is forced back in a forward direction so that the upper 55 end thereof finally slides under the step 58 of the arm 54 to releasably retain the lever in its vertical position as shown in the full lines in Figure 3. The solenoid 35, of course, may include the usual means in the form of a spring, 60 not shown, to retract its core 36. Thus, the parts are once more restored to a starting position ready for the operator to make another selection.

The switches 39 and 73 shown, are merely typical of one manner of control for obviously the 65 making and breaking of the circuits for the solenoids 35 and 63 may be controlled manually, or automatically in any way desired, depending upon the character of the vender or amusement apparatus organization with which the selector may find use.

It can now be seen that an improved selector has been provided, which achieves all of the desirable objects for the invention heretofore re-cited.

70 It is the intention to cover all changes and

modifications of the example herein shown for the sake of disclosure, which do not constitute departures from the spirit and scope of the invention, as indicated by the appended claims.

What is claimed is:

5 1. A circuit selector adapted to be carried in a wall member, said selector comprising a bracket, a plate carried in the bracket for endwise movement, a handle element for moving said plate, a plurality of normally open switches carried adjacent the bracket, a cross shaft carried by the bracket between the plate and switches, a plurality of levers individually carried by said shaft for pivotal movement and each lever including switch engaging means to close an adjacent 10 switch, an electromagnetic device carried by the plate and movable thereby to a position adjacent a lever without operating same, whereby when the electromagnetic device is subsequently energized a lever is moved to engage and close a selected switch.

15 2. A circuit selector adapted to be carried in a wall member, said selector comprising a bracket, a plate carried in the bracket for endwise movement, a handle element for moving said plate, a plurality of normally open switches carried adjacent the bracket, a plurality of movably mounted switch closing members carried by the bracket respectively adjacent each switch, an electromagnetic device carried by the plate and 20 movable therewith to positions selectively adjacent the switch closing members without closing the switches, said members being individually operable by the electromagnetic device when the latter is subsequently energized to cause closing 25 thereby of a selected switch, and means carried by the bracket to limit the movement of the levers in the direction of the switches.

3. A circuit selector adapted to be carried in a wall member, said selector comprising a bracket, a plate carried in the bracket for endwise movement, a handle element for moving said plate, a plurality of normally open switches carried adjacent the bracket, a plurality of movably mounted switch closing members carried by 40 the bracket respectively adjacent each switch, an electromagnetic device carried by the plate and movable therewith to positions selectively adjacent the switch closing members without operating said members, said members being individually operable by the electromagnetic device when the latter is subsequently energized to cause closing 45 thereby of a selected switch, and means operatively associated with the bracket for yieldingly and releasably locking the plate 50 in any selected position of adjustment.

4. A circuit selector adapted to be carried in a wall member, said selector comprising a bracket, a number of normally open switches carried by the bracket, a manually movable member carried 60 by the bracket including an electromagnetic device movable therewith to positions alining the electromagnetic device with a selected switch but without closing same, a movably mounted member carried adjacent each switch and operable by the electromagnetic device to engage and close a selected switch when the electromagnetic device is energized, automatically acting means carried by the bracket adjacent each movably mounted member for releasably latching the members in 65 their position free of a switch or when they are in switch engaging positions, and means for resetting a member from a switch closing position to a position free of a switch to enable the latter to open.

5. A circuit selector adapted to be carried in a wall member, said selector comprising a bracket, a plurality of normally open spring switches carried by the bracket, a plate carried by the bracket for shifting movement, a solenoid carried by the plate for movement therewith whereby said solenoid may be aligned with a selected switch without closing same, and means pivotally carried by the bracket between the solenoid and switches and 10 operable by the solenoid when the latter is energized to engage and close a selected switch.
6. A circuit selector adapted to be carried in a wall member, said selector comprising a bracket, a plurality of normally open spring switches carried by the bracket for shifting movement, a solenoid carried by the plate for movement therewith whereby said solenoid may be aligned with a selected switch without closing same, means for releasably locking the 15 plate in a selected position of adjustment, and means movable by the solenoid when the latter is energized from a normal position free of a switch to a position engaging and closing said switch.
7. A circuit selector adapted to be carried in a wall member, said selector comprising a bracket, a plurality of normally open spring switches carried by the bracket, a plate carried by the bracket for shifting movement, a solenoid carried by the plate for movement therewith whereby said solenoid may be aligned with a selected switch without closing same, a plurality of independent levers pivotally carried on a common axis by said bracket, with the levers aligned with the respective switches and in a normal position free thereof, a plurality of bell crank levers pivoted on a common axis and respectively positioned to engage the aforesaid levers, said bell crank levers including means for engaging and releasably locking the switch levers in either a position free of the 30 switches or in a position engaging the switches, said switch levers being operable by the solenoid when the latter is energized selectively to engage and close the switches.
8. A selector comprising a bracket, a plurality of normally open upright spring switches carried by the bracket, a plate selectively movable on the bracket relative to the switches, a solenoid carried on the plate to move therewith, a plurality of upright pivoted levers respectively carried by the bracket for movement from a position free of the 35 switches to a position engaging and closing same, means releasably latching said levers in either position, the levers being selectively operable by the solenoid when energized to close a selected switch.
9. A selector comprising a bracket, a plurality of normally open upright spring switches carried by the bracket, a plate selectively movable on the bracket relative to the switches, a solenoid carried on the plate to move therewith, a plurality of upright pivoted levers respectively carried by the bracket for movement from a position free of the 40 switches to a position engaging and closing same, means releasably latching said levers in either position, the levers being selectively operable by the solenoid when energized to close a selected switch.
- selected switch, and a movably mounted member carried by the bracket and operable to engage the latches to free a lever in switch closing position for movement to switch opening position.
10. A selector comprising a bracket, a plurality of normally open upright spring switches carried by the bracket, a plate selectively movable on the bracket relative to the switches, a solenoid carried on the plate to move therewith, a plurality of upright pivoted levers respectively carried by the bracket for movement from a position free of the 45 switches to a position engaging and closing same, means releasably latching said levers in either position, the levers being selectively operable by the solenoid to close a selected switch, a spring pulled swingably mounted bail carried by the bracket, and electromagnetically operated means to swing said bail to a position for releasing the latches to free a lever in switch closing position for movement to switch opening position.
11. A selector comprising a channel bracket presenting an end wall and spaced side walls, a plate carried on the bracket for lateral sliding movement along the end wall, a solenoid carried on the plate, a plurality of normally open switches carried in spaced relationship on the bracket between its side walls, a cross shaft carried in the side walls of the bracket, and pivoted levers carried by the shaft in positions respectively adjacent the switches and movable by the solenoid when energized to engage and close a selected switch.
12. A selector comprising a channel bracket presenting an end wall and spaced side walls, a plate carried on the bracket for lateral sliding movement along the end wall, a solenoid carried on the plate, a plurality of normally open switches carried in spaced relationship on the bracket between its side walls, one edge of the plate having corrugations therein, means for yieldably latching the plate in any desired position of adjustment relative to a selected switch, said means comprising a spring pressed lever carried by the bracket and having a roller at its free end to engage said corrugations, and means carried by the bracket and operable by the solenoid to engage and close a selected switch.
13. A selector comprising a channel bracket presenting an end wall and spaced side walls, a plate carried on the bracket for lateral sliding translational movement along the end wall, a solenoid carried on the plate, a plurality of normally open switches carried in spaced relationship on the bracket between its side walls, said end wall having an elongated opening formed therein, a pin connected to the plate and passed through said opening to the opposite face of the end wall, a knob on the pin whereby said plate may be manually shifted in relation to the bracket, said knob, pin and plate being bodily movable as a unit, and means operable by the solenoid when energized to engage and close a selected switch.

FRANK G. NICOLAUS.

CHARLES J. BREITENSTEIN.
